The image shows a screenshot of the Lattice HR platform. At the top, there is a navigation bar with links for 'Platform', 'Solutions', 'Why Lattice', 'Resources', 'Pricing', 'Company', 'Sign in', and 'Request a demo'. A 'BETTER TOGETHER' button is also present. The main headline reads 'Every tool you need to power strategic HR'. Below the headline, a subtext says 'See how Performance connects with the rest of the Lattice platform.' A large '+' icon is positioned at the bottom center, connected by lines to six rounded rectangles representing different tools: 'Performance' (with a circular arrow icon), 'Grow' (with a person icon), 'Engagement' (with a heart icon), 'OKRs & Goals' (with a target icon), 'Compensation' (with a person icon), and 'Analytics' (with a bar chart icon). To the right of these tools is a 'Raise guidance' section showing a table of performance ratings for three employees: Sarah Johnson, Mel Miller, and John Smith. The table includes columns for 'NAME', 'PERFORMANCE RATING', 'CURRENT PAY', and 'RAISE GUIDANCE'. A call-to-action 'Learn more >' is located to the right of the table.

NAME	PERFORMANCE RATING	CURRENT PAY	RAISE GUIDANCE
Sarah Johnson		\$ 100,000.00	\$ 4,000.00
Mel Miller		\$ 105,000.00	\$ 4,200.00
John Smith		\$ 95,000.00	\$ 2,000.00
